ARTIFICIAL LEATHER COMPOSITION

Horace A. Sheesley, Portland, Maine, assignor to
Tufide Products Corporation, Portland, Maine,
a corporation of Maine

No Drawing. Application October 30, 1935,
Serial No. 47,512

9 Claims. (Cl. 91—68)

This invention relates to artificial leather compositions and more particularly to a composition comprising a mixture of fibres and a binder which can be economically and effectively used in the manufacture of articles heretofore generally made of good quality leather.

It has heretofore been proposed in the manufacture of artificial leather compositions, to mix liquid latex with the fibre either in the beater 10 or following the beater operation. The latex when so treated is inclined to coagulate and gum, resulting in an uneven dispersion of the binding material through the fibres when the sheet is formed.

15 It has also been proposed to form artificial leather compositions by providing multi-ply sheets of pulp tissue, each separate sheet being coated with a binding material before pressing the several sheets together. Another method 20 proposes to puncture the superimposed tissue sheets by needle holes through which it has been attempted to force the latex binding material. The products formed by these known processes are not satisfactory since the binding medium 25 is not uniformly dispersed in and through the fibres, with the result that the material presents areas of weakness where it can be torn or broken under test or in service. The composition thus formed also readily splits into layers which 30 is most undesirable.

The vulcanizing ingredients heretofore used in the composition also have a tendency to coagulate or congeal the binder before it has an opportunity to become completely dispersed in and 35 through the fibres.

Latex-fibre leather substitutes as heretofore made, have a rubbery surface characteristic which is very unlike the surface of real leather and immediately identifies it as a leather substitute. The rubbery surface characteristic results from the concentration of excessive amounts 40 of rubber solids by deposition upon the outer surface of the material. The latex solids covering the surfaces of the composition become sticky 45 under pressure and especially so in damp warm weather. This sticky surface characteristic is especially undesirable where the latex pulp material is to be used for the inner soles of shoes. The body weight on the foot exerts pressure on 50 these inner sole materials causing the feet or stockings to stick to the latex coating with resulting discomfort to the wearer. This sticky surface characteristic is also undesirable in other articles or leather products as will be evident to 55 those skilled in the art.

Fibre-latex composition materials heretofore manufactured lack breathing qualities and are inclined to sweat the feet of the wearer. Such compositions also have a tendency to peel or rub off at the surface, leaving exposed unbound 5 fibres beneath, which in turn will rub off even more rapidly. This further characteristic makes fibre-latex composition materials as heretofore manufactured undesirable for inner soles, causing discomfort to the foot and undue wear on 10 the hose. Washing will not remove latex deposited on clothing or hosiery and for this reason latex pulp compositions heretofore manufactured have not found a ready use where the composition would come into frictional contact with 15 clothing or other washable fabrics.

An object of this invention is to provide an improved artificial leather composition which is strong, flexible and durable, which will not readily split, crack, tear or break, which is comfortable to the wearer and remarkably adapted 20 for the inner soles of shoes, which has the feel of genuine leather, which is inexpensive to manufacture, and which is remarkably adapted for many uses where genuine leather has heretofore been used.

Another object of this invention is to provide an artificial leather composition in which the fibres are felted and interlaced and thoroughly impregnated and homogeneously saturated with 30 an improved binder, producing a material which is remarkably adapted for uses where genuine leather has heretofore been used.

Another object of this invention is to provide an improved process for manufacturing artificial 35 leather compositions of the type herein described.

Another object of this invention is to provide a binding solution for fibrous materials which can be easily and quickly applied to the fibrous material, which will thoroughly penetrate the 40 fibrous layer homogeneously and completely coat the individual fibres so as to form a homogeneous bond between the fibres.

Another object of this invention is to provide a binding solution having a latex component 45 which will quickly and thoroughly penetrate a fibre mass, and which will thereafter quickly and economically expel the liquid component of the solution and leave the solid binding material evenly and thoroughly dispersed through 50 the felted mass and inseparably united to the fibres.

Other objects of this invention will become apparent as the disclosure proceeds.

The fibres forming a part of my improved 55

artificial leather composition may comprise either cotton, linen, sisal, hemnequin, hemp, and wood pulp fibres or a mixture of one or more of these. The well known varieties of wood pulp, such as 5
5 Mitscherlich (sulphite) pulp, soda pulp, bleached sulphite pulp, sulphate (Kraft) pulp, may all be used. Old rope and rag pulp also make an excellent material if the fibres still retain their normal tensile strength. It is, of course, necessary to beat and wash the rope or rag fibre material so as to remove all dirt and decayed fibres. It is evident that the stronger and tougher the fibre used the tougher and stronger will be the finished material.

10 The binder with which the fibres are saturated preferably contains liquid latex as an ingredient. A high grade glue may be added to the liquid latex along with a small amount of ammonia and formaldehyde, and a highly volatile organic liquid. 15
15 Glue of the blood albumin type is preferably used but fish glues, hide glues, egg albumin, and other fat-free animal glues may also be used. Casein glue may be used, but it is not usually recommended due to the fact that it has a tendency to decompose in warm and moist weather. The 20
20 compound should be free from zinc oxide which unfavorably affects the desired binding action of the latex or glue constituents.

25 The volatile organic liquids preferably used contain alcohol as the principal constituent. A 30
30 liquid should be selected which is highly volatile, which will readily escape from the fibres and which will preferably aid in removing the less volatile liquid materials, such as water, from the 35
35 composition during manufacture. A very satisfactory volatile liquid has been made from approximately 85 to 90% ethyl alcohol and approximately 10% of a mixture of methyl alcohol, acetone, ethyl acetate and aviation gasoline. The 40
40 cheaper alcohols, such as wood alcohol or grain alcohol, preferably 170 proof, and upwards, can be used.

45 A small amount of liquid ammonia is added to stabilize the latex in solution and prevent a premature precipitation of the latex solids. A small amount of formaldehyde may also be added to assist in tanning the glue and prevent odors from the resultant product.

50 By way of example, the following formula has been found satisfactory for the purpose of this invention. To 8½ pounds of liquid latex of good commercial grade is added 6 pounds of blood albumin glue which comprises approximately 1 pound of solid blood albumin and 5 pounds of water. The quantities above referred to are representative and of course will vary within fairly wide limits since liquid latex from various sources 55
55 may vary in amount of solid constituents and various sources of blood glue also vary in water absorptive qualities. A liquid latex containing approximately 40% rubber solids provides a desirable material. Sufficient water should be added to the solid blood albumin to reduce the same to a soft but non-flowing gel.

60 For blending purposes approximately ½ to 2 pounds of a readily volatile liquid comprising a major portion of ethyl alcohol is added. The escape of the liquid constituents of the binder from the fibres may be facilitated by increasing the quantity of alcohol added. The proportion of aqueous ammonia which is added will depend upon the amount of ammonia contained in the commercial liquid latex. As a general rule, however, most commercial grades of latex will require the addition of from ½ to 2 pounds of liquid

75 ammonia to every 8½ pounds of latex. Approximately ½ ounce of formaldehyde added to the above constituents is sufficient to remove any odors from the material and exert the desired tanning and hardening action on the blood albumin glue. A binder material containing approximately the above proportion of ingredients is liquid and free flowing and can be readily incorporated into the fibrous mass to homogeneously coat the fibres and bind them into a solid 10 mass.

15 In summarizing the effective formula above referred to the binder may contain approximately 18 to 22% rubber solids from latex, 4 to 7% of blood albumin giving a solid constituent of approximately 25%, a liquid constituent of 70 to 74%, and a gaseous constituent of 1 to 4%. The normally liquid and gaseous constituents would comprise approximately 60 to 65% water, 6 to 8% ethyl alcohol (which might also contain approximately 1% or less of methyl alcohol), ethyl acetate and aviation gasoline, together with approximately 1 to 1% of formaldehyde and from 1 to 3% ammonia.

20 The above formula is given by way of example 25 only. The amount of liquid latex used may vary within wide limits depending upon the type of material desired. A strong, tough and flexible material results when liquid latex in the approximate proportions above given are used. If a considerable increase in liquid latex is made the material will begin to have a rubbery feel and will be inclined to sweat the feet when used as an inner sole.

25 Commercial latex varies in solid latex constituents anywhere from 25 to 60%. Since the solid constituent is the important component it is always desirable to test each batch of latex for rubber solids before combining the same into the mixture. Different types of albumin blood glue 30
30 will also absorb different quantities of water varying from 1 part dry glue to 4 to 7 parts water, depending upon the source of the albumin which varies in different animals. Sufficient water 35
35 should be added to the dry glue to produce a soft but non-flowing gel. A composition comprising approximately 1 part latex solid to 1 part glue gel will produce a material which possesses hardness and considerable stiffness. A composition containing approximately 4 parts latex solid to 1 part glue gel makes an excellent leather substitute, highly adaptable for inner soles and quarter linings for shoes. The percentages used may 40
40 thus be varied from approximately 1 part latex solid to 1 part glue gel (producing a relatively 45 hard stiff material) to approximately 9 parts latex solids to 1 part glue gel (producing a highly flexible tough and strong material). in the compression tank is connected by suitable flexible hose to a spray gun which drives the liquid binder into a loosely felted web of fibres to thoroughly impregnate, and saturate the fibres and provide a uniform homogeneous bond there-

5. It is well known that concentrated alcohols exert a setting, cooking or congealing action on albumin glues and also operate to congeal the 10 latex. It is of the utmost importance that no congealing action of the latex or glue gel mixture takes place until the fibres have been thoroughly impregnated and saturated with the binding material. I overcome this congealing action 15 by feeding the alcohol or other highly volatile constituent into the pressure feed line leading to the nozzles or into the compression tank as appears most convenient and desirable. The alcohol mixes with the latex-glue gel material as it 20 passes through the spray gun and it is therefore given no appreciable time or opportunity to effect congealing action of the latex or glue gel until the fibres have been uniformly coated therewith. The formaldehyde, which also exerts a certain 25 hardening or tanning action on the gelatine, is also preferably fed into the pressure stream where it has no opportunity to effect the glue gel until the fibres have been thoroughly impregnated.

The fibres comprising cotton, linen, hemp or 30 wood pulp fibres or a mixture of one or more of these, are fed in dry condition into a carding or shredding machine. The shredder acts to thoroughly mingle and intertwine the various fibres in a loose felted mass. The loose felted mass of 35 fibres is evenly distributed in a layer of the proper thickness and then subjected to the action of the spray guns which project the liquid binder into the loosely felted mass of dry fibres, until all the fibres have been uniformly impregnated and 40 coated with the liquid binder. An initial compacting pressure is then exerted on the sprayed mass of fibres as the saturated web is carried along on a moving belt. The alcohol or highly volatile material quickly escapes from the fibres 45 by evaporation and carries with it a considerable quantity of aqueous material contained therein. Before escaping, however, the alcohol as well as the formaldehyde exerts a setting and hardening action on the latex solids and glue binders with 50 the result that the saturated web quickly assumes a self-sustaining tensile strength.

When the saturated web has assumed an initial set a powdered material is dusted uniformly over the surfaces of the web to give the finished material the desired leathery feel and remove surface stickiness. Wood flour provides a satisfactory surfacing material, although other powdered materials, either of animal, vegetable or earthy origin may be used. After passing through the 55 duster applicator the web moves into a drying tunnel where it is heated to approximately 212° F. and upwards to 250° F. more or less. The greater proportion of volatile liquid constituents, particularly water, are driven off and evaporated from the felted web in the drying tunnel. To hasten the drying action, the drying tunnel may be reduced to a partial vacuum by means of vacuum pumps and suitable means, such as condensing apparatus, may be provided to recover the volatile material, such as alcohol, used in the process.

During the travel of the webbing through the tunnel dryer or immediately following its travel through the tunnel dryer, the webbing may be passed through one or more sets of compression

rollers to compact and compress the material together into a homogeneous sheet. The sheet then passes through dryers preferably of the festoon type and the sheet run through further compression rollers or a leathering machine positioned either within or outside the festoon dryer. The finished artificial leather composition can then be rolled into a roll or cut into strips of the desired size.

A layer of carded felted fibres approximately 10 two inches in thickness will reduce down to a completed artificial leather composition approximately $\frac{1}{16}$ of an inch thick. The looseness of the felted layer through which the binding solution is sprayed can thus be readily understood. 15 In addition, the felted condition of the fibrous constituent gives a finished material of uniform strength in all directions.

An unusually tough and strong material having the desirable characteristics of genuine leather 20 may be formed by combining approximately one gallon of the liquid latex glue binder with approximately 5 pounds of wood pulp. The finished artificial leather product preferably contains from 50 to 65% substantially dry pulp and from 35 to 50% solid binder material. These proportions of course can be varied to give materials having a more fibre-like composition by reducing the binder constituent to 20 or 30% and increasing the fibre material to 70 or 80%. To make a material having more rubber-like characteristics the 30 binder material can be increased to 60 or 65% of the total composition. If strength and toughness is not of prime importance, the liquid latex can be materially decreased and the glue component proportionately increased to produce a product which is stiffer and yet is strong and porous and possesses a leathery feel. Respirability or "breathing" of natural leather is thus 35 readily simulated, in varying degrees, in the 40 products of the present invention.

The albumin glue increases the resistance of the resultant product to water and heat and increases its firmness and hardness. The glue constituent appears to assist thorough penetration of the fibres and a complete dispersion of the solid particles of the binder among the fibres. The volatile solvents, as above described also greatly assist in the driving off or removal of the water constituent, thus shortening the time for drying 45 of the finished material and furthermore assists making the product homogeneous. While the above binder compound flows readily and appears to be even more liquid than the latex constituent, it nevertheless has the unusual and desirable characteristic of drying out with greater rapidity than 50 latex compounds heretofore used, and at the same time obtaining a more thorough penetration and a more uniform dispersion of the solid binding material in the fibres. The raw materials can be 55 prepared and fed into suitable apparatus which carries the material progressively during manufacture until the finished product is obtained in one continuous process thus effecting great saving in cost of manufacture over processes heretofore used. The wood flour is relatively inexpensive and is applied and rolled into the surface of the material while the web of saturated fibres moves through the apparatus, effecting further saving in cost of manufacture. Thus a product 60 which has superior qualities over artificial leather compositions heretofore made is produced at a great saving in cost. The product is especially adapted for shoe manufacture and particularly 65 inner soles. Actual tests of the material in use 70 75

as inner soles have demonstrated that my artificial leather composition is comfortable to the feet, substantially respirable and waterproof, prevents the entry of moisture through the shoe and yet does not draw the feet nor cause the feet to sweat or heat.

5 My artificial leather composition may be given a surface appearance closely resembling suede leather by dusting suitably dyed ground cotton, 10 hemp or sisal linters over the surface of the material. Highly desirable wall and floor coverings of great strength and wearing qualities can also be made by using rope or hemp fibres in the composition. The finished material may be 15 made of any desired thickness ranging from two irons to twenty-four irons.

10 The invention further consists in the new and novel compositions and in the constituents as set forth in the specification and all equivalents thereof, including the new and useful arrangement and combination of steps in the process herein described and more particularly set forth in the claims annexed hereto.

What is claimed is:

15 1. An artificial leather sheet material including a body portion comprising from 50 to 70% of felted and compressed wood pulp fibres and a binder material for the fibers, said wood pulp fibres extending in all directions with no defined 20 directional arrangement, the said binder material consisting of homogeneous dehydrated latex, and blood albumin, tanned in situ.

25 2. A respirable artificial leather sheeting including a homogeneous body portion comprising 50% and upwards of felted and compressed wood pulp fibers extending throughout the body portion in all directions, said unoriented fibers being interbonded and joined in a tough mass of high 30 substantially uniform tensile strength in all directions, the bonding material for the said sheeting comprising the solid residuum of a liquid flowable mixture of latex, blood albumin glue and a tanning agent.

35 3. A respirable non-laminated artificial leather sheeting including a homogeneous body portion comprising 50-70% of compressed wood pulp fibers extending in all directions, said fibers being interbonded and joined in a tough mass of high 40 substantially uniform tensile strength in all directions, the bonding material for the said sheeting comprising the solid residuum of a liquid flowable mixture of latex, blood albumin glue and a tanning agent.

45 4. A respirable artificial leather sheeting including a homogeneous body portion of compressed wood pulp fibres extending in all directions, said fibers being interbonded and joined in a tough mass of substantially high tensile strength in all directions, the bonding material 50 for the said sheeting comprising the solid residuum of a liquid flowable mixture of latex,

5 blood albumin glue and a tanning agent, and a pulverulent surfacing of natural cellulosic materials incorporated on and in the surfaces of said sheeting.

5 A respirable artificial composition sheeting 5 having a leathery finish including a homogeneous body portion of compressed natural cellulosic fibres extending in all directions, said fibers being interbonded and joined in a tough mass of high 10 substantially uniform tensile strength in all directions, the bonding material for the said sheeting comprising the solid residuum of a liquid flowable mixture of latex, albumin glue and a tanning agent, and a pulverulent surfacing of natural cellulosic materials incorporated on and 15 in the surfaces of said sheeting, the said cellulosic materials comprising dust of cellulosic fibres.

6 A respirable artificial composition sheeting having a leathery suede finish including a homogeneous body portion of compressed natural cellulosic fibres extending in all directions, said fibers being interbonded and joined in a tough 20 mass of high substantially uniform tensile strength in all directions, the bonding material for the said sheeting comprising the solid residuum of a liquid flowable mixture of latex, 25 albumin glue and a tanning agent, and a pulverulent surfacing of natural cellulosic materials incorporated on and in the surfaces of said sheeting, the said cellulosic materials comprising 30 dust of ground cotton linters.

7 A respirable artificial composition sheeting having a leathery suede finish including a homogeneous body portion of compressed natural cellulosic fibres extending in all directions, said 35 fibers being interbonded and joined in a tough mass of high substantially uniform tensile strength in all directions, the bonding material for the said sheeting comprising the solid residuum of a liquid flowable mixture of latex, 40 albumin glue and a tanning agent, and a pulverulent surfacing of natural cellulosic materials incorporated on and in the surfaces of said sheeting, the said cellulosic materials comprising 45 dust of ground hemp fibre.

8 A respirable artificial leather including approximately 60% of matted wood pulp fibers extending in all directions, each fibre being impregnated and coated with substantially 40% of the residuum of a mixture including approximately 30% rubber latex solids and 10% blood albumin glue tanned during the formation of the artificial leather in situ.

9. An artificial leather including substantially 50 to 70% of matted wood pulp fibers extending 55 in all directions, the fibres being severally impregnated and coated with a mixture comprising approximately 20 to 40% rubber latex solids and approximately 6 to 15% albumin tanned during the formation of the artificial leather in situ.

HORACE A. SHEESLEY.
